UNITED STATES PATENT OFFICE

168,641

PRESSURE REGULATOR OR SIMILAR
ARTICLE

Theodore A. St. Clair, South Euclid, and Richard C. Krall, Euclid, Ohio, assignors to The Weatherhead Company, Cleveland, Ohio, a corporation of Ohio

Application January 24, 1952, Serial No. 18,188

Term of patent 14 years

(Cl. D78—1)

To all whom it may concern:

Be it known that we, Theodore A. St. Clair and Richard C. Krall, citizens of the United States, residing at South Euclid, Ohio, and Euclid, Ohio, respectively, have invented a new, original, and ornamental Design for a Pressure Regulator or Similar Article, of which the following is a specification, reference being made to the accompanying drawings, forming a part hereof:

In the drawings Fig. 1 is a top plan view of a pressure regulator showing my new design;

Fig. 2 is a front elevation thereof;

Fig. 3 is a bottom plan view of the pressure regulator as shown in Fig. 2;

Fig. 4 is a side view taken on the right of Fig. 2; and

Fig. 5 is a side view taken on the left of Fig. 2.

We claim:

The ornamental design for a pressure regulator or similar article, as shown.

THEODORE A. ST. CLAIR.
RICHARD C. KRALL.
